UNITED STATES PATENT OFFICE.

ALLEN J. GARVER, OF CLARKSTON, WASHINGTON.

APPARATUS FOR TREATING ORES.

1,243,505.

Specification of Letters Patent. Patented Oct. 16, 1917.

Application filed December 8, 1914, Serial No. 876,061. Renewed March 13, 1917. Serial No. 154,598.

To all whom it may concern:

Be it known that I, ALLEN J. GARVER, a citizen of the United States, and a resident of Clarkston, in the county of Asotin 5 and State of Washington, have invented a new and Improved Apparatus for Treating Ores, of which the following is a full, clear, and exact description.

An object of the invention is to provide 10 a simple, convenient, efficient and inexpensive plant for carrying out the roasting of ores whereby the general efficiency of the apparatus used in the plant for handling ores is greatly increased. A further object 15 of the invention is to utilize the fumes arising from the roasted ores by directing the fumes into the ore tank and there converting them into acid, which reacts with the ores, thus dispensing with the use of independent acid chambers.

With the above and other objects in view, 20 the nature of which will more fully appear as the description proceeds, the invention consists in the novel construction, combination and arrangement of parts as herein 25 fully described, illustrated and claimed. In the accompanying drawings, forming part of the application, similar characters of reference indicate corresponding parts in all 30 the views, and—

Figure 1 is an elevation, partly in section, of my gravity plant;

Fig. 2 is an enlarged section through the rotary roaster;

Fig. 3 is a cross section on line 3—3 of Fig. 2;

Fig. 4 is a longitudinal section through the ore tank; and

Fig. 5 is a cross section on line 5—5, 40 Fig. 4.

Before proceeding to a more detailed description of my invention it must be clearly understood that although the plant illustrated and described herein makes use of 45 pebbles, the process can be carried out without the use of same.

Referring to the drawings, 6 is a gravel box dominating the plant and disposed adjacent a conveyer 7 which is adapted to deliver pebbles into the box. The box 6 is provided with a delivery hopper 18 controlled by a gate 19 through which pebbles may be discharged into an inclined chute 8, through which chute the ores are fed.

55 The bottom 20 of the chute is a raceway formed of a number of steps slightly over-

lapping each other and causing the ore and pebbles fed thereon to drift to the outlet of the chute. The bottom of the chute forms the top of a passage 21 which is in communication with a furnace 9 from where it conveys the hot air and gases, thereby heating the ores as they descend the raceway. A funnel 22 connects the outlet of the chute 8 with a rotary roaster 10 intended to receive 60 the ores from the chute 8. The chute 8 is connected to a tank 8^a adapted to contain a basic or acid solution which can be fed from the tank into the funnel 22. Said funnel is connected to a stationary cup-shaped 65 head 23 rigid on a support 24.

Within the head 23 (see Fig. 2) is a baffle plate 25 for directing the ores into the rotary roaster 10 which roaster is formed of a cylindrical shell 26 having at one end an 70 annular flange 27 fitting snugly around and in axis with the head 23. An annular partition 28 is mounted within the cylindrical shell 26 adjacent the head 23 through which the baffle enters the shell 26. The other 75 axially-opened end 37 engages snugly a box 38.

The shell is provided with circular bearing rings 34 which rest upon rollers 35, the latter being revolvably supported on pedestals 36. The shell is also provided with a circular rack 29 in mesh with a pinion 31 which is carried by a shaft 32 mounted in suitable bearings 33.

The box 38 is provided with a trap 40 90 normally closed by tension members 43 connected with a bar 42 engaging the trap. This arrangement permits the operation of the trap at the will of the operator. Said box 38 is provided with a delivery pipe 45 95 leading to a revoluble ore tank 11, locked at one end, and below the rotary roaster 10.

The shell 26 is provided with a lining formed of bricks 46 and 48, the bricks 48 being directed radially and dominating the 100 bricks 46 between which they are located. In the joints between the bricks clay rods 47 are provided obliterating the joints between the successive bricks. Each brick 48 is provided with a triangular channel or recess 50 105 terminating in a notch 51 at the apex nearest the box 38. The arrangement of the bricks 48 is such that the ores resting loosely in the recesses 50 will drift and escape through the notch 51; see top of Fig. 2.

110 The ore tank 11 is preferably in the shape of a cylinder having a circular rack 52 ad-

2
jacent one end in mesh with a pinion 54, the pinion being carried by a revoluble shaft 56 properly supported by a bearing 55. Within the ore tank 11 is an annular partition 57 in contact with staves 60 and troughs 58. The troughs are directed radially and dominate the staves. Each of the troughs is provided with a series of triangular recesses or channels 61, each channel having a notch 59 at the apex nearest to the discharge end of the ore tank. The function of the staves and troughs in the ore tank is similar to that of the bricks forming the lining of the roaster, previously described. Hoops 70 encircle the staves and troughs 58 and lock them together.

A disk 62 located at the ends of the staves and troughs and in engagement therewith forms the discharge end of the ore tank. A 20 spider 63 forming an integral part of the head 62 bears on a member 65 which carries a tubular member 64 projecting through the head 62. A chute 67 is provided within the ore tank adjacent the head 62 which has an 25 outlet 68 through the tubular member 64, not merging with the passage 66 of the tubular member. The bearing carrying the tubular member 64 and the chute 67 is supported by a pedestal 69.

30 A head 71 similar to the disk 62 is provided between the staves adjacent the partition 57, the dominating parts of the trough 58 being located between the partition 57 and the disk 62. A spider 72 rigid with the 35 head 71 bears on a member or gudgeon 75 projecting through the head 71 and carried by a pedestal 74. The gudgeon 75 and the tubular member 64 have additional supports 76 which help to support the ore 40 tank 11.

The delivery pipe 45 projects through the gudgeon 75 into the ore tank 10 to deliver the goods through the opening of the annular partition 57. The part of the delivery pipe 45 located in the gudgeon 75 receives 45 an ejector pipe 77, (see Fig. 4) which leads to the outlet of a pump 79 the inlet of which is connected to a tank 80 mounted on pedestals 81. The tank is adapted to contain 50 proper solutions for the purpose of treating the ores after the latter have been roasted. In place of connecting the projector pipe 77 with the pump, the same can be connected to a steam supply. The jet of steam in such 55 a case will suck the fumes and dust from the roaster into the ore tank. In place of providing an ejector 77 for causing the suction in the pipe 45, a partial vacuum may be operated in the pipe 45 by any other suitable 60 means. The use of the above means will prevent the clogging of the delivery pipe, and in using steam heat will be added to the mass of ore in the tank and, consequently, the conversion of the ore facilitated.

65 The tubular member 64 is connected to a

condenser 13 by a tube 83, the latter being in turn connected to a tube 84 arranged for producing an aspirating effect in the tube 83. The tube 84 leads to a tank 85 for holding a liquid or compressible fluid to 70 cause the aspirating effect. The condenser 13 comprises a tank 86 mounted on supports 87 and containing a suitable liquid which serves to receive and dissolve the residual substance resulting from the condensation of 75 the fumes, gases and vapors.

The ore fed gravitationally upon the steps of the bottom 20 of the chute 21 is mingled with pebbles from the box 6 which pass through the gate 19 and hopper 18. The 80 pebbles accompanying the ore serve to keep the bottom 20 clean and also to keep both the rotary roaster and the ore tank in good condition by preventing the material from clogging therein. The products of combustion of the furnace 9 passing through the 85 passage 21 heat the ores passing in the opposite direction over the steps of the bottom 20, causing the ores to be roasted. The receptacle 8^a may contain nitrate of soda or sulfuric acid in accordance with the character of the ores to be treated. If sulfuric acid is employed in its reaction with the ores, it forms sulfates and also other various complex compounds containing sulfur. The 90 ore entering the funnel 22 glides on the baffle plate 25 and falls on to adjacent bricks 46 and 48 of the revolving ore roaster 10.

The ore, as above stated, is mixed with 100 pebbles, which are preferably of small size, and in their travel they carry with them fine ore particles. The momentum and smoothness of the pebbles enable them to gravitate with greater facility than the ore would do and, consequently, carry the ore with them. The use of pebbles renders the feed of the ore more uniform and homogeneous. As 105 the shell 26 of the roaster 10 is rotated, the various bricks 48 scoop up all of the loose material into their triangular recesses and lift the material nearly to the top, then allow it to slide in successive streams. Due to the shape of the recesses 50 the ore is caused to progress step by step as the rotation of the roaster continues; this result being attained, as can be easily seen, by the 110 triangular shape of the recesses 50.

The rotary roaster may be subjected to heat applied externally if desired, but when 115 sulfuric acid is used it is not necessary, the ore being sufficiently heated in the roaster due to the chemical reaction and the initial heat received by the ore previous to its entrance into the roaster. During the passage of the ore through the rotary roaster 120 10 the same is subjected to the action of the liquid supply from the receptacle 8^a; consequently, the original chemical composition of the ore is changed to some extent, various salts being broken up and others formed. 130

The material thus treated passes over the end 37 of the roaster and drops into the head 40 from where a delivery pipe 45 leads it into the revolving ore tank 11.

5 The ejector pipe 77, whether connected to a pump or to a jet of steam, causes the fumes and dust in the roaster to flow into the ore tank, to which it may be said the same is aspirated, thus preventing the clogging 10 of the delivery pipe 45. In the ore tank the troughs 48 provided with their recesses 61 carry the mass of material, similar to what has been described for the roaster 10. The ore so far treated in the ore tank 15 is then delivered to the chute 67 from where it is conducted to a sieve 14, the fine ore passing through the sieve and the pebbles being guided to the conveyer 7 which returns the pebbles to the box 6. The ejector 20 pipe 77 supplying steam or a liquid to the ore tank 11 adds heat to said tank and, further, helps the chemical reaction between the fumes carried from the roaster and the ore present in the tank, and also 25 with the substance supplied by the ejector. Gases and vapors present in the ore tank 11 are aspirated into the condenser 13 due to the suction caused by the provision of the ejector 84. The result of the condensation may 30 be considered as a by-product.

From the foregoing description, taken in connection with the accompanying drawings, the advantage of the construction of the plant shown will be readily understood 35 by those skilled in the art to which the invention pertains; and while I have described the principle of operation, together with the plant and method of operating the same which I now consider to be the best 40 embodiment thereof, I desire to have it understood that the method and plant shown are merely illustrative and that such changes may be made as are within the scope of the appended claims.

45 Having thus described my invention, I claim as new and desire to secure by Letters Patent:

1. In a gravity plant for treating ore, a chute adapted to receive ore to be treated, 50 a furnace the products of combustion of which are adapted to contact with the chute, whereby the ore is progressively heated, a tank associated with the chute whereby a chemical compound may be added to the ore 55 passing through the chute, a rotary roaster adapted to receive the ore mixed with the chemical compound, said roaster comprising a plurality of triangular recesses causing the mixture to move step by step toward the outlet and fall intermittently during 60 its movement toward the outlet, a rotary ore tank adapted to receive the ore from the rotary roaster, an ejector adapted to force the contents of the rotary roaster 65 into the rotary tank, said rotary roaster

having similar triangular recesses on its inner lateral surface whereby the contents thereof are caused to move progressively toward the delivery end and fall intermittently during the movement, a condenser associated with said rotary ore tank, and means for forcing the gaseous and vaporous substances from the rotary tank into the condenser. 70

2. In a gravity plant for the treatment 75 of ore, a chute adapted to receive comminuted ore, a furnace associated therewith the product of combustion of which furnace is adapted to heat said chute, the ore fed through the chute moving in a direction 80 opposite to the product of combustion coming from the furnace, means associated with the chute for adding to the ore passing through the chute a compound adapted to react chemically with the ore, a rotating 85 closed chamber adapted to receive ore coming from the chute, said closed chamber having means on the inner lateral surface to cause the ore to fall intermittently while the same is passing through said chamber, 90 a second similar chamber adapted to receive the mixture from the first chamber, an ejector associated with said second chamber for facilitating the transit of the ore mixture from the first into the second chamber, 95 said ejector adapted to supply heat to said second chamber, and a condenser associated with said second chamber for eliminating therefrom the gaseous and vaporous substances resulting from the treatment of 100 the ore.

3. In a gravity plant for the treatment of ore, a revoluble closed chamber, and longitudinal members at the inner lateral surface thereof, said longitudinal members 105 having a series of triangular-shaped recesses each having a notch at the apex nearest to the delivery end of the chamber.

4. In a gravity plant for the treatment of ore, a pair of revoluble closed chambers 110 each having longitudinal scooping members at the inner lateral surface, each of said scooping members having a series of triangular-shaped recesses at the attacking side, each of said recesses having a notch through 115 which the material accumulated in the recesses is discharged, the recesses and notches being so related to the delivery end of each chamber that gravity causes the material in said recesses to gradually creep to the delivery end by falling intermittently in said chamber. 120

5. A revolving ore roaster comprising a rotary shell having a cylindrical form, a lining for said shell, said lining being of 125 bricks provided with grooves, a filling within said grooves, and other bricks connected with said first-mentioned bricks and provided with compartments for raising and spilling ores and the like. 130

6. In a revolving ore roaster the combination of a cylindrical member adapted to revolve, bricks mounted therein and having curvature, said bricks being so disposed as to form a lining for said cylindrical member, other bricks provided with compartments and secured intermediate said first-mentioned bricks and projecting radially toward the center of said cylindrical member, said last-mentioned bricks each being provided with a substantially triangu-

lar compartment and with a notch merging into said compartment for discharging the contents thereof.

In testimony whereof I have signed my name to this specification in the presence of two subscribing witnesses.

ALLEN J. GARVER.
